Patented May 25, 1965

201,235

TOY MOTOR

Carl J. Merl, Erie, Pa., assignor to Louis Marx & Co., Inc.,
New York, N.Y., a corporation of New York

Filed June 22, 1964, Ser. No. 80,519

Term of patent 14 years

(Cl. D90—1)

FIG. 1

FIG. 2

Des. 201,235

PAGE 2

FIG. 3

FIG. 4

FIG. 5

FIG. 6

FIG. 1 is a top plan view of a toy motor embodying my new design;

FIG. 2 is a front elevational view thereof;

FIG. 3 is a rear elevational view thereof;

FIG. 4 is a bottom plan view thereof;

FIG. 5 is a left side elevational view thereof; and

FIG. 6 is a right side elevational view thereof.

I claim:

The ornamental design for a toy motor, as shown.
